(21) Appl. No.: **29/387,858**

(57) **CLAIM**

(22) Filed: **Mar. 18, 2011**

The ornamental design for a mast for a material handling vehicle, as shown and described.

(51) **LOC (9) Cl.** 12-05

DESCRIPTION

(52) **U.S. Cl.** **D34/35; D34/34**

FIG. 1 is a top, right, rear perspective view of a mast embodying our new design coupled to a material handling vehicle;

(58) **Field of Classification Search** D34/34,

FIG. 2 is a top, right, rear perspective view of the mast of FIG. 1 removed from the material handling vehicle;

D34/35; 180/89.12, 89.13, 89.17; 187/222,

FIG. 3 is a rear elevational view thereof;

187/237

FIG. 4 is a front elevational view thereof;

See application file for complete search history.

FIG. 5 is a right elevational view thereof, the left elevational view being a mirror image thereof;

(56) **References Cited**

FIG. 6 is a top plan view thereof; and,

FIG. 7 is a bottom plan view thereof.

The broken line representations in the views are for illustrative purposes only and form no part of the claimed design.
